Patented Mar. 12, 1918.

FIG. 1.

FIG. 2.

FIG. 3.

FIG. 4.

FIG. 5.

FIG. 6.
Inventor:
Robert F. Carpenter
By *Wm. H. Monroe*
Attorney.

UNITED STATES PATENT OFFICE.

ROBERT F. CARPENTER, OF CLEVELAND, OHIO.

SHEET-METAL CABINET.

1,259,358.

Specification of Letters Patent. Patented Mar. 12, 1918.

Application filed August 14, 1916. Serial No. 114,733.

To all whom it may concern:

Be it known that I, ROBERT F. CARPENTER, a citizen of the United States, and resident of Cleveland, in the county of Cuyahoga and State of Ohio, have invented certain new and useful Improvements in Sheet-Metal Cabinets, of which I hereby declare the following to be a full, clear, and exact description, such as will enable others skilled in the art to which it appertains to make and use the same.

The objects of the invention are to provide a simple, clean and rigid form of sanitary partition to be erected between toilets in a gentlemen's toilet room, and suitable for use in hotels, schools and office or factory buildings, and elsewhere, wherever public convenience must be considered.

It includes the construction from sheet metal supports or frames and paneled surfaces in which there are no exposed corners or cracks in which dust or dirt can collect, or in which infectious germs can multiply.

It also includes a form of construction which requires the minimum amount of material to erect.

The invention comprises the hollow vertical sheet metal posts and horizontal hollow moldings or frame members to which the inclosed panels are integrally secured.

It includes unitary partitions easily put in place and means for attaching them in front and rear, and further includes hinged doors with a spring action, for the hinge to prevent them from opening, and a leveling device by means of which they can be set in the vertical position.

It also includes connecting means for each pair of partitions, comprising transverse bars secured to vertical extensions of the vertical posts at the front of the device, thus forming a complete cabinet or section.

The invention further comprises the combination and arrangement of parts and construction of details hereinafter described, shown in the accompanying drawings and specifically pointed out in the claim.

In the accompanying drawings Figure 1 is a front elevation showing the vertical columns at the front of one section, the door, the connecting bar between the partitions and portions of sections adjoining the same; Fig. 2 is a vertical section of one section on horizontal central line; Fig. 3 is a transverse section of Fig. 1 on line *b*—*b* Fig. 2; Fig. 4 is an enlarged elevation showing

the hinges and the construction of the same; Fig. 5 is a transverse section of corner of one vertical post and the outer edge of the door enlarged from Fig. 3; Fig. 6 is a detail view showing the means of adjusting the vertical edge of each post.

In these views A, A, are vertical posts formed of enameled sheet steel bent to form an angular tube, and having their parallel vertical edges approximated closely together, and turned outwardly to form parallel flanges A', A'. B is a panel formed of similar enameled sheet metal, the vertical front edge of which is inserted at B' between the said parallel flanges, and is secured therebetween preferably by spot welding.

The post A forms the support for the front edge of the panel B and its rear edge is turned at right angles at B² to form a flange through which bolts B³ are passed to secure it to the rear wall. When a vertical vent space is required as at C, a separate vertical back wall D formed of sheet metal is secured to said flanges, thus including the back wall in the metallic section as a complete unit.

The vertical side panels are spaced from the floor at E, thus providing perfect ventilation through the section. The rear wall however, extends to the bottom to prevent water from running backward. Each side panel is reinforced at its upper and lower edges by means of hollow rigid bar I, I, respectively, constructed in precisely the same manner as the vertical posts, and composed of sheet metal bent into tubular form and provided with marginal parallel flanges I', I', between which the adjacent edge of the panel is secured, preferably by spot welding, which leaves no securing means of any sort visible.

The abutting edges of the several bars and post are preferably then butt welded together.

The top, bottom and front edges of the panel are thus rigidly held and each side becomes a unit with its post. The vertical posts are extended above the upper edges of the sides at J and capping members K, K, are inserted therein. Shanks K' are provided for that purpose. A strong bar or tube L is then extended across the front through openings L' in the caps, which properly secure the sides in their spaced positions.

The upper extremities of the posts are also rigidly connected with the rear wall by means of horizontal bars or tubes L^2 inserted in elbows L^3 in said cups.

5 These rearwardly directed bars or tubes can be secured to the rear wall by means of flanged sleeves L^4 and to the caps by set screws or can be rigidly welded thereto.

This device is simple in construction, rigid 10 in all directions that strain can be brought upon them.

A door R is hung to an edge of one of the vertical posts, in each section, by means of the upper and lower pivot bearings R' , R'' 15 upon the post, and pintle pins R^3 , R^4 upon the upper and lower edges of the door. A coiled spring R^5 in one of the bearings always keeps the door shut. One end of this spring is inserted in the bearing R^6 at S and 20 the other in the bearing at S' .

The door is prevented from closing 25 noisily or passing the entrance by means of a bar or pad or soft rubber or felt F or similar material which is supported against the opposite post in the manner of a shoulder at T , by means of an angle shown at T' , Figs. 3 and 5. A handle T^2 is also attached upon the outer side for opening the door. Means are shown for adjusting the posts to 30 stand vertically so that the edges of the doors will be vertical. These consist of sockets W , W , having extended lugs W' through which lag bolts W^2 extend and are adjustably sunk in lead sockets W^3 in the 35 floor.

The door is constructed in the same manner as the partitions from a sheet metal panel R and reinforcing hollow sheet metal

bars R^7 , R^7 , provided with inwardly turned flanges R^8 , R^8 , which inclose the edges of 40 the panel between them, and to which they are preferably spot welded, thus producing a perfectly rigid and practical form of construction having the appearance of a panel with molded stile and molded horizontal 45 rails.

When enameled and erected, and the vertical posts properly adjusted, an indestructible, attractive and perfectly clean toilet or cabinet is provided which can be constructed 50 in one section or in as many sections as may be desired.

Having described the invention, what I claim as new and desire to secure by Letters Patent is:

In combination, a sanitary cabinet or section comprising spaced partition walls of sheet metal terminating a distance above the floor, and a rear wall secured thereto, and sheet metal tubular reinforcing members for the front and top and bottom edges of said partitions, said tubular members provided with longitudinal flanges between which the edges of said sheet metal walls are secured, the reinforcing members for the front edges 65 of said partition walls, forming vertical posts supporting said partitions, and extending above and below the same, and means for rigidly connecting the upper ends 70 of said posts.

In testimony whereof, I hereunto set my hand this 27th day of July, 1916.

ROBERT F. CARPENTER.

In presence of—

FRANK J. MERRICK,
Wm. M. MONROE.
